UNITED STATES PATENT OFFICE.

JOSEPH E. WAINWRIGHT, OF BROOKLYN, NEW YORK.

VALVE-LIFTING DEVICE.

1,392,373.

Specification of Letters Patent.

Patented Oct. 4, 1921.

Application filed November 15, 1920. Serial No. 424,128.

To all whom it may concern:

Be it known that I, JOSEPH E. WAINWRIGHT, a citizen of the United States, residing at Brooklyn, in the county of Kings and 5 State of New York, have invented certain new and useful Improvements in Valve-Lifting Devices, of which the following is a specification.

This invention relates to valve spring lifters and has for its object the production of a simple and efficient device which will facilitate the lifting of a valve spring in order to permit the removal of the retaining pin and the valve stem from engagement with 15 the valve spring.

Another object of this invention is the production of a simple and efficient mechanism whereby the operator may conveniently lift the valve spring seat from engagement with the retaining pin carried by 20 the valve stem with the least amount of difficulty.

A still further object of this invention is the production of an efficient tool which may 25 be universally used upon or in connection with various forms of motors for the purpose of efficiently lifting the valve spring seat and permitting the removal of the valve from the motor.

With these and other objects in view, this invention consists of certain novel constructions, combination and arrangement of parts as will be hereinafter fully described and claimed.

In the drawings Figure 1 is a side elevation showing the tool coöperating with an improved form of clamp.

Fig. 2 is a side elevation of my improved valve spring seat lifter in an expanded or 40 open position showing the manner of lifting the valve spring seat.

Fig. 3 is a top plan view of the lifting jaws which are adapted to engage the work.

Fig. 4 is a detail perspective of one section of one of the jaws.

Fig. 5 is a side elevation of a modified form of my tool applied directly to my improved form of clamp.

Fig. 6 is a section taken on line 6—6 of 50 Fig. 5.

Fig. 7 is a section taken on line 7—7 of Fig. 5.

Fig. 8 is a perspective view of my improved clamp.

Fig. 9 is a vertical section through the

support for the adjusting rod and compression member.

Fig. 10 is a section taken on line 10—10 of Fig. 9.

Fig. 11 is a side elevation of the shank 60 through which the adjusting rod is adapted to extend.

Fig. 12 is a side elevation of the lifting yoke carried by the lower end of the clamp and which is adapted to extend under the 65 valve spring seat.

By referring to the drawings it will be seen that 20 designates the body of the valve spring seat lifter tool which is of a lazy-tong structure, carrying a handle 21 at 70 its rear end. The body 20 carries at its forward end a pair of upper jaws 22 and a pair of lower jaws 23. The upper jaws 22 are pivoted upon the bearing pin 24 carried by the link section 25 and the lower jaws 23 are pivotally mounted upon the journal pin 26 carried by the link section 27. The upper jaws 22 are milled as indicated at 28 upon their upper faces and the lower jaws 23 are milled similarly upon their lower 75 faces, to produce an efficient gripping space for engagement with the work. Attention is invited to the fact that the lower jaws 23 are formed so as to fit snugly around the tappet, whereas the upper jaws 28 are spaced 80 from each other at a greater distance than the jaws 23. In this way the jaws 23 will constitute an efficient anchor for the tool while the same is in operation and at the same time the widened jaws 28 will facilitate the lifting of the valve spring while the device is in operation.

Each section of the jaws 22 and 23 is provided with a rearwardly extending finger 29, each finger having a beveled or inclined face 30 near its rear end for facilitating the sliding of the finger 29 under the bearing rollers 31 carried by the respective ends of the links of the lazy-tong structure. Furthermore when the tool is in the position shown in Fig. 1, the bearing rollers 31 will constitute an efficient clamp for holding the jaws in a proper position for insertion under a valve spring seat or in engagement with the valve clamp which may be used in conjunction with the tool.

As shown in Fig. 7 the respective links of the body of the tool which comprises a lazy-tong structure are connected by means of journaled pins 32 upon which the bear- 105 110

ing rollers 31 are mounted, these pins being flattened as indicated at 33 for the purpose of retaining the rollers 31 upon the pins 32. The respective links of the body 20 are pivotally connected at their crossing points by means of the pins 34 which also carry suitable rollers similar to the rollers 31 and when the tool is in a position shown in Fig. 1 it will be seen that the jaws 22 and 23 will be firmly clamped in a closed position between the forward pin 34 and the end pin 32.

When it is desired to insert the tool for the purpose of lifting the valve spring seat, the jaws 22 and 23 are moved to the position shown in Fig. 1 and the forward ends of the jaws are forced in between the tappet support and the valve spring seat or between the respective collars carried by the clamp which will be hereinafter fully described. The handle 21 is then pushed inwardly to cause the body or lazy-tong structure 20 to assume the positions shown in Fig. 2 of the drawings, thereby raising the valve spring seat to the position shown in Fig. 2 of the drawings.

From the foregoing description it will be seen that a very simple and efficient structure has been produced for facilitating the lifting of the valve spring seat which tool will produce a maximum amount of power for lifting the valve spring seat with a minimum amount of effort on the part of the operator.

In Figs. 5 and 6 I have shown a modified form of my invention wherein a suitable clamp 35 is employed at the outer end of which is carried an adjusting head 36, this head 36 being pivotally mounted as at 37 and being adjustably held in a set position by means of a thumb screw 38 working through an arc shaped slot 39 formed in the adjusting head 36. This head 36 is provided with an internally threaded collar 40, through which collar 40 extends the threaded adjusting rod 41. A compression section 42 is held in engagement with the compression rod 41 through the medium of a lazy-tong structure 43, this lazy-tong structure being of similar design and construction to that previously described with respect to the tool illustrated in detail in Figs. 1 and 2 of the drawings. The compression section 42 extends through a guiding shank 44, which shank 44 is provided with a plurality of laterally extending web portions 45 having inwardly tapering sides 46 to facilitate the placing of the shank within the upper end of the valve aperture 60 or port formed in the motor. A laterally extending pin 45 is carried by the lower end of the compression section 42 to prevent the shank 44 from dropping off the lower end of the compression section 42. This compression section 42 is provided

with a pointed lower end 46' to facilitate the engagement of the same with the upper end of a valve. It should be understood that the clamp 35 may be formed of any suitable or desired construction for the purpose of engaging the under face of the valve spring seat and may be formed similarly to the structure illustrated in detail in Fig. 8 described in the following.

Attention is now particularly invited to Figs. 8 to 12 inclusive wherein I have shown a modified form of the invention disclosing what is known to the trade as a valve clamp or more particularly known in some cases as a C clamp. This clamp comprises a substantially U-shaped body 47 having a lower arm 48 and an upper or over hanging arm 49. The lower arm 48 carries a substantially U-shaped valve seat lifting yoke 50 shown clearly in Figs. 8 and 12 and this yoke 50 is provided with a straight upper face 51 and an inclined or curved lower face 52 to facilitate the placing of the yoke 50 under the valve spring. The over hanging arm 49 carries a head 52 which is pivotally mounted at 53 upon the arm 49. A thumb nut and screw 54 is employed for the purpose of locking the head 52 in engagement with the arm 49 at a desired angle, the thumb screw passing through a suitable arc shaped slot 55 as shown clearly in Fig. 11. The head 52 is provided with an internally threaded shank 56, through which internally threaded shank 56 extends the adjusting rod 57. This adjusting rod 57 is provided with a transversely extending pin 58 at its upper end to facilitate the rotation thereof and the proper adjustment of the rod 57. A lock nut 59 is threaded upon the rod 57 and is adapted to jam against the upper edge of the shank 56 to efficiently hold the adjusting rod 57 in a set position. A collar 60 is fixedly secured to the rod 57 and normally limits the upward movement of the rod 57 through the shank 56. This rod 57 however may be adjusted downwardly through the shank 56 as will be obvious. The rod 57 is provided with an unthreaded extension 61 at its lower end, upon which unthreaded extension 61 is slidably mounted a compression head 62. A collar 63 is secured to the upper end of the compression head 62 and a set screw 64 is passed through the collar 63 and engages a flattened portion 65 upon the extension 61 to hold the compression head against rotation or accidental removal from the extension 61. A tapered cap 66 is carried by the lower end of the compression head and comprises an undercut extension 67 under which is compressed the lower edge of the body of the compression head as indicated clearly in Fig. 9. This construction will produce a very efficient means for attaching the cap or tapered end 66 to the body of the

compression head. From the foregoing description it will be seen that by employing the lazy-tong structure in conjunction with the gripping jaws as clearly set forth, a 5 self locking and unlocking device has been produced which may be released at any point. It is also desired to point out that the arrangement and construction of the jaws will produce a parallel lip for locking 10 the tool at any height.

By considering Fig. 8 it will be obvious that by hinging the head portion upon the clamp as illustrated in detail in Fig. 11, the 15 tool may be placed in position in the minimum amount of time, this tool being especially adapted for use in connection with what is generally known to the trade as "V motors" or "V blocks" and having ports.

By referring particularly to Figs. 5 and 6 20 of the drawings it will be seen that a very efficient device has been produced in the nature of the guiding shank 44. By providing the edges 46 which taper toward the bottom of the shank, it will be seen that the 25 shank will fit various sizes of ports or openings and at the same time efficiently support the tool in engagement therewith.

Attention is also called to the fact that the tool which is illustrated in Figs. 1 and 30 2 is especially adapted for use in conjunction with the auxiliary clamp shown in Fig. 8. The projecting jaws 22 and 23 of the tool extend between the respective collars 60 and 35 63 for forcing the compression head downwardly when the tool is moved from a position shown in Fig. 1 to the position shown in Fig. 2. In other words the structure or tool comprising the lazy-tong construction is especially adapted for use in conjunction 40 with the clamp shown in Fig. 8.

It of course should be understood that certain detail changes in mechanical construction may be employed without departing from the spirit of the invention provided 45 these changes fall within the scope of the appended claims.

The claims are as follows:

1. A valve spring lifting tool comprising a body formed of a lazy-tong structure, 50 valve spring lifting jaws pivotally mounted upon the outer end of said body, and overhanging means carried by the side edges of said body for engaging said jaws and limiting the swinging movement thereof in one 55 direction.

2. A valve spring lifter comprising a body formed of a lazy-tong structure, valve spring lifting jaws pivotally carried upon said body and provided with rearwardly extending 60 fingers, and roller bearings carried by the side edges of said body and engaging said fingers for limiting the swinging of said jaws in one direction and facilitating the moving of said jaws to an open position.

65 3. A valve spring lifter comprising a body

formed of a lazy-tong structure, valve spring lifting jaws carried by the outer end of said body and pivotally mounted thereon, said jaws provided with rearwardly extending fingers, roller bearings carried by the side 70 edges of said body and engaging said fingers for limiting the swinging movement of said jaws in one direction, each finger provided with a beveled rear end adapted to engage certain of the rollers for constituting a lock 75 against the opening of the tool by pressure from the forward end of the tool.

4. A valve spring lifting tool comprising a body, valve spring lifting jaws carried by said body and pivotally mounted thereon, 80 each jaw comprising a pair of sections, said sections being similarly constructed and having outwardly flared outer ends for facilitating the gripping of the work to be acted upon, and means carried by said body 85 for holding said jaws in substantially parallel relation when in various adjusted positions.

5. A clamp for use in conjunction with valve spring lifting tools comprising a body, 90 means carried by one end thereof engaging a valve spring seat, an adjusting rod carried thereby, and a compression head slidably mounted upon said adjusting rod.

6. A clamp of the class described comprising a body, a spring seat engaging device, an adjustable hinge upon the clamp, means for clamping said head in an adjusted position at a desired angle upon said clamp, a threaded rod adjustably mounted through 100 said head, and a compression head slidably mounted upon said adjusting rod and adapted to be engaged by a tool for forcing the same longitudinally of the unthreaded portion of said rod.

7. A clamp of the class described comprising a body, a valve spring lifting portion, a head hingedly secured to said clamp, means for locking said head at an adjusted angle with respect to said clamp, said head provided with an internally threaded portion, an adjusting rod extending through said head, a locking nut for locking said rod in an adjusted position, said rod provided with an enlarged collar secured thereto, a slidably 110 mounted compression head mounted for sliding movement upon the lower end of said rod, a set screw for limiting the longitudinal movement of said compression head upon said rod, and centering means formed upon 120 the lower end of said compression head.

8. A clamp of the class described comprising a body, a compression head slidably supported upon said body and comprising a supporting shank, a sleeve slidably mounted 125 upon said shank, an abutment collar carried by the upper end of said sleeve, and a tapering point carried by the lower end of said sleeve and clamped in engagement with said sleeve.

9. In combination with a clamp of the character described, a compression member, a guiding shank for receiving said compression member, said guiding shank provided with a plurality of laterally extending web portions having inclined side edges tapering toward the bottom thereof for facilitating the placing of said shank in various size openings for supporting said compression member, and a compression tool associated with said compression member.

10. In combination with a clamp provided with a compression member adjustably supported thereon, of a tool comprising a body

formed of a lazy-tong structure, and jaws 15 carried by the forward end of said lazy-tong structure and adapted to engage said compression member for actuating said compression member.

11. A valve spring lifter comprising a 20 body of a lazy tong structure, valve spring lifting jaws pivotally mounted upon the outer end of said body, and means carried by said body for limiting the swing of said jaws in one direction and holding said jaws 25 at all times in parallel relation.

In testimony whereof I affix my signature.

JOSEPH E. WAINWRIGHT.
